(57) **CLAIM**

The ornamental design for a charging stand for electronic device, as shown and described.

DESCRIPTION

FIG. 1 is a front side perspective view of a charging stand for electronic device showing our new design;

FIG. 2 is a back side perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof;

FIG. 9 is a reference view thereof, showing a state with a lid open; and,

FIG. 10 is a reference view thereof, showing a state with an electronic device placed.

The broken lines shown in FIG. 10 depict environmental structure and form no part of the claimed design.
